Primary Examiner — Cynthia R Underwood*(74) Attorney, Agent, or Firm* — Lowe Graham Jones PLLC(57) **CLAIM**

I claim the ornamental design for a turntable, as shown and described.

DESCRIPTION

FIG. 1 is a top perspective exploded view of a turntable, showing my new design.

FIG. 2 is a front elevational exploded view of the turntable.

FIG. 3 is a rear elevational exploded view of the turntable.

FIG. 4 is a left side elevational exploded view of the turntable.

FIG. 5 is a right side elevational exploded view of the turntable.

FIG. 6 is a top plan exploded view of the turntable.

FIG. 7 is a bottom plan exploded view of the turntable; and,

FIG. 8 is a top perspective view of turntable.

The broken lines depict portions of the article that form no part of the claimed design.

1 Claim, 8 Drawing Sheets(56)
